TUFTING MACHINE

John M. Gladish, Chattanooga, Tenn., assignor of one-half to Robert Blair Cannon and one-fourth to Willie Mae Gladish, both of Chattanooga, Tenn.

Application May 25, 1934, Serial No. 727,515
Renewed June 9, 1939

39 Claims. (Cl. 112—2)

This invention relates to a tufting machine, and more especially to a sewing machine equipped with means for severing a strand, and intermittently delivering the severed portions of the strand to a fabric as it is passed beneath the presser foot of the machine, where the severed portions of the strand are sewed successively onto the fabric by means of a conventional needle mechanism supplied with a conventional sewing thread.

I have shown the invention as being applied to a sewing machine of standard make, though it is evident that a special machine embodying all of the features shown attached to the conventional machine could be manufactured, placing the parts in different forms and in different positions without departing from the spirit of the invention.

It is an object of this invention to provide a sewing machine having means associated therewith, and driven in timed relation thereto for delivering a strand or a plurality of strands to the apparatus and intermittently severing the ends of the strands and seizing the severed portions and intermittently delivering the severed portions to the fabric immediately in front of the advancing presser foot, whereby the severed portions of the strand are caught by the line of stitches and sewed to the fabric. When these severed portions are properly fluffed or otherwise treated they have a very ornamental effect.

It is a further object of this invention to provide a sewing machine, and especially a tufting machine whereby a strand of yarn, or a plurality of strands of yarn may be delivered to the machine equipped with means for severing the yarn into short lengths and seizing the lengths and delivering the same to the fabric as it advances underneath the presser foot, and whereby the line of stitches will cross the delivered and severed strand to sew it to the fabric, thus providing tufting apparatus independent of any looping mechanism. This apparatus provides a finished article which has no visible portion of the tufts supplied thereto appearing on the lower side of the fabric, there being only a line of stitches indicating the course of the applied tufts to the fabric.

The apparatus hereinafter shown and described is particularly adaptable to producing bed spreads, curtains, trimmings for dresses, draperies, pillow cases, applying fringes to the edges of fabrics or garments, and many other varied uses. Means are also provided in the mechanism for adjusting the length of the severed portions

of the strand, that is, the strands can be cut very short and delivered and sewed onto the fabric, or they can be cut longer in several varying lengths to produce several different effects. Also means are provided whereby a plurality of different length colored strands can be delivered to the yarn handling and yarn severing mechanism, whereby, when the severed portions of the strand are sewed onto the fabric the various colored portions of the yarn will appear in the finished tuft in various places, thus producing varied and heretofore unaccomplished ornamental effects.

Some of the objects of the invention having been stated, other objects will appear as the description proceeds, when taken in connection with the accompanying drawings, in which—

Figure 1 is a side elevation of the left-hand portion of an ordinary sewing machine with my invention applied thereto;

Figure 1A is a side elevation of the right-hand portion of a sewing machine, showing a variable speed unit and also a stitch reversing mechanism applied thereto;

Figure 2 is a sectional view taken along the line 2—2 in Figure 1;

Figure 3 is a sectional view taken along the line 3—3 in Figure 2;

Figure 4 is a sectional view taken along the line 4—4 in Figure 2;

Figure 5 is a vertical sectional view taken along the line 5—5 in Figure 1;

Figure 6 is a vertical sectional view taken along the line 6—6 in Figure 1;

Figure 7 is a detailed view showing in elevation the strand guide for guiding the strands of yarn into my mechanism at desired points;

Figure 8 is a sectional view taken along the line 8—8 in Figure 2 showing in detail the knife for severing the strands of yarn;

Figure 9 is a sectional view through the knife and taken along the line 9—9 in Figure 8;

Figure 10 is a horizontal view taken along the line 10—10 in Figure 8;

Figure 11 is a sectional view taken along the line 11—11 in Figure 4 showing the pressing wheel in elevation;

Figure 12 is a sectional view taken along the line 12—12 in Figure 4;

Figure 13 is a sectional view taken along the line 13—13 in Figure 4 showing the means for splicing the upper ring;

Figure 14 is a vertical sectional view taken along the line 14—14 in Figure 1;

- Figure 15 is a sectional view taken along the line 15—15 in Figure 3;
- Figure 16 is a vertical sectional view taken along the line 16—16 in Figure 1;
- 5 Figure 17 is an isometric view showing an attachment adapted to be pivoted beneath the throat plate of a sewing machine for securing the end of the bobbin thread in position when the fabric is removed from the machine;
- 10 Figure 18 is a sectional view similar to the upper portion of Figure 16, but showing the means for engaging the tuft of yarn in a slightly different position;
- 15 Figure 19 is another view similar to the upper portion of Figure 16, but showing the yarn or tuft engaging means in lowered position just prior to being lowered to its lowermost position to where the tuft is sewed onto the fabric;
- 20 Figure 20 is a horizontal sectional view taken along the line 20—20 in Figure 19;
- Figure 21 is a vertical sectional view taken along the line 21—21 in Figure 19;
- 25 Figure 22 is a horizontal sectional view taken along the line 22—22 in Figure 16;
- 25 Figure 23 is an isometric view of the yarn engaging means;
- 30 Figure 24 is an enlarged sectional view similar to the central portion of Figure 16, but showing the yarn clamping means in its lowermost position as the yarn is being sewed onto the fabric;
- 35 Figure 25 is a horizontal sectional view taken along the line 25—25 in Figure 24;
- Figure 26 is a vertical sectional view looking at the left-hand portion of Figure 1, but showing a modified form of the invention;
- 40 Figure 27 is a vertical sectional view similar to the upper right hand portion of Figure 2, showing the cam arrangement adapted to operate the modified form;
- 45 Figure 28 is a vertical sectional view similar to Figure 14 but showing the cam arrangement adapted to operate the modified form;
- Figure 29 is a sectional plan view taken along the line 29—29 in Figure 26;
- 45 Figure 30 is an isometric view of the yarn or tuft clamping means adapted to operate in the modified form;
- 50 Figure 31 is an isometric view of the means for grasping the tuft of yarn and conducting it beneath the presser foot;
- Figure 32 is a sectional view taken along the line 32—32 in Figure 1A, and showing means for reversing the direction of oscillation of the feed plate;
- 55 Figure 33 is a sectional view similar to the central portion of Figure 11 showing in the present instance six strands of yarn compressed into the groove in the feed ring;
- 60 Figure 34 is a plan view of the tuft of yarn as shown in Figure 33, as this strand of yarn will appear on the fabric when sewn thereto by the conventional stitch in a sewing machine;
- 65 Figure 35 is a plan view of the tuft of yarn as shown in Figure 34 after it has been washed and fluffed;
- Figure 36 is a plan view similar to Figure 35 but showing another effect that can be produced when different colored strands of yarn are placed at different positions;
- 70 Figure 37 is another view similar to Figure 35 but showing another effect produced;
- Figure 38 is another view similar to Figure 35 but showing still another effect that can be produced by varying the colors, combinations and 75 positions of the strands of yarn.
- Referring more particularly to the drawings the numeral 10 denotes the base member of an ordinary sewing machine which has integral therewith and projecting upwardly therefrom a hollow upright standard 11. Standard 11 has a 5 horizontally projecting portion or goose-neck 12 which extends to the left and has on the end thereof, as shown in Figure 1, the conventional head 13. The mechanism associated with the head 13 has not been shown in detail because it 10 is not deemed necessary; however, it might be stated that it is conventional in all respects and is present in the ordinary commercial sewing machine. It is with this head that my invention is adapted to operate. By any suitable means, such as set screw 14, I secure a plate 15 to head 13. A lug 16 is secured to the face of plate 15 by any suitable means such as screw 17 and secured to the end of lug 16, as at 18, is a supporting bar 19, said supporting bar extending laterally on each side of point 18 and supporting the base ring 20. Base ring 20 extends around the plate 15 and head 13, and is supported on the front side of the sewing machine (Figure 1) by a suitable notch cut in the plate 15. A groove is cut in the inner periphery of base ring 20, in which is adapted to fit the upper half-rings 26 and 27. In Figure 13 the detail of the splice of these two rings is clearly shown.
- The object of splicing these rings is to make 30 them easily removable so that a different ring with a different spacing of notches on different sizes of grooves therein can be substituted for cutting different lengths of tuft or varying sizes of strands; therefore, the upper ring is cut in semi-circles forming two pieces 26 and 27. It is evident that suitable screws 28 and 29 can be threaded into the ring at the splicing point to hold the ring in position. These rings can be removed merely by removing screws 28 and 29, and a different set of semi-circular pieces can be placed therein to accomplish a different result.
- A plurality of radially disposed notches 30 are cut in the semi-circular members 26 and 27 comprising the upper ring, in which is adapted to 45 move a suitable cutting apparatus, such as a knife 31. By referring to Figures 2, 8, 9 and 10 the details of this knife and associated parts are clearly shown. Secured to the lower side of ring 20, by any suitable means such as screw 33 is a bracket 32, which in turn, is secured to a supporting member 34 by suitable means such as a screw 35.
- Secured to supporting member 34 are suitable washers 36 and 37 against which is adapted to 55 slide a slotted bar 38. Disposed on the near side of bar 38 (Figure 8) are washers 39 and 40, and these washers are penetrated by screws 41 and 42, which penetrate slots 43 and 44 in bar 38, and are threadably secured in support 34. By this arrangement it is seen that vertical movement of bar 38 and knife 31 is allowed.
- Disposed on one side of blade 31 is a supporting member 45 which in turn is held against slotted bar 38, and disposed on the other side is a similar member 46. Another member 47 is placed against the surface of plate 46, and all of the plates 45, 46 and 47 are securely held to bar 38 by means of screw 48. In Figure 3 the knife 31 is shown in its lowermost position, as it is severing the strand or strands, while in Figure 8 the knife is shown in a raised position.
- Pivots connected to bar 38, as at 56, is a link 57, which projects upwardly and has its upper end pivotally connected as at 58 to an arm 59. 75

Arm 59 is threadedly secured in sleeve 60, which sleeve is rotatably mounted on shaft 61, which in turn, is secured to plate 15. The left-hand end of shaft 61, as shown in Figure 1, is supported by a suitable link 62 which projects upwardly and encircles a horizontally disposed shaft 63.

Shaft 63 is supported in the upper portion of plate 15, and is also supported at its right-hand end in bearing 64, said bearing being supported by a post 65, which projects downwardly, and is secured in the upper portion of the sewing machine. Suitable arms 66 and 67 are integral with sleeve 60, and fastened to these arms 66 and 67 are perches 68 and 69, to which are secured flexible members such as cables 70 and 71 respectively. These members 70 and 71 project downwardly and are adapted to encircle a hub 72, and are secured to this hub as at 73. Hub 72 is rotatably mounted in plate 15 as at 74, and 20 operates the tuft clamping mechanism which will presently be described.

Arm 66 has secured thereto, as at 76, a cam lever 75, which projects upwardly and is adapted to contact cam 77 at all times. Likewise, to arm 25 67 is secured as at 78 a cam lever 79 which will contact cam 80 at all times. Both of these cams are secured to a hub 81, which in turn is fixedly mounted on shaft 63. It is evident that as the shaft 63 rotates that the cam levers 75 and 79, 30 which are contacting cams 77 and 80 will cause the arms 66 and 67 to oscillate, thereby oscillating the shaft 61 and arm 59. This will cause the knife and its associated parts to have oscillatory motion and penetrate the slots 30 in the upper 35 ring comprising portions 26 and 27, a predetermined intervals, and cut the yarn or the tufts in the desired lengths.

It will be noted by referring to Figure 8 that a suitable slot 86 is cut also in the lower ring 20 40 at the point where the knife 31 penetrates the slot, this will allow the knife to move downwardly a sufficient amount to sever the yarn without causing the blade to contact ring 20 and dull the cutting edge. It will be noted in Figures 45 1, 18 and 19 that the ring 20 is not quite a complete circle as its ends are spaced apart at the front to allow the tuft removing means to have access to the tufts to transfer them to the fabric.

50 Rotatably mounted on bar 19 are rollers 81 and 82 as at 83 and 84 respectively. Roller 81 has a plate 85 disposed on the upper side thereof which projects over the upper surface of the upper ring to hold it in its proper position whereas roller 55 82 has a flange on the upper side to accomplish this purpose. These rollers engage the inner surface of the upper ring and diminish the friction due to the rotation.

Secured to the lower side of ring 20 by any 60 suitable means such as screws 88 and 89 is a bar 87. The left-hand portion of bar 87 as shown in Figure 3 has pivotally secured as at 90 a bell crank 91, said bell crank having a horizontally disposed arm 92, which pivotally supports a link 93. The upper end of link 93 is secured in sleeve 94 by means of set screw 95, and in the upper 65 end of sleeve 94 another link 96 is in a like manner secured in the sleeve 94 by means of set screw 97. These links 93 and 96 have conically shaped ends into which the leading edge of a screw 98 is adapted to fit.

By loosening up on set screws 95 and 97 and tightening on screw 98 minute adjustment as to the overall length of links 93 and 96 can be 70 adjusted. Link 96 is supported by a suitable

bearing 99, which bearing is secured to plate 15 by any suitable means such as screw 100. The upper end of link 96 has a button 101 integral therewith, and this button is adapted to contact a cam 102.

It will be seen in Figures 1, 3 and 6 that cam 102 is adjustably mounted on the hub 103 by any suitable means such as a washer 104, and a stud bolt 105, said stud bolt being adapted to be threadably secured in hub 103 and penetrating a suitable slot 106, in the cam 102.

It will be noted that hub 103 is fixedly secured to shaft 63 by any suitable means such as a rivet 103a, and by loosening the stud bolt 105 the throw of the cam can be varied. When the stud bolt has been loosened the cam can be moved so that its eccentricity with respect to shaft 63 will vary.

Bell crank 91 has an upwardly extending arm 111, which has abutting its upper end a link 112, 20 said link 112 extending horizontally as shown in Figures 3 and 4, and having its other end abutting a suitable projection 113. Projection 113 is integral with rack member 114, which is held in position by means of an arm 115, which projects 25 toward the observer as shown in Figure 4, and has a point on the end thereof which abuts a lug 116 secured in plate 15.

A suitable spring 117 has one end thereof secured to rack 114 and the other end secured to 30 pin 118, said pin 118 being secured in supporting bar 19. This spring normally pulls the rack member and its associated parts against the link 112, and likewise holds the point on the end of member 115 in contact with lug 116.

It will be noted in the drawings that for every slot 30 there is a notch 120 corresponding thereto. These notches are adapted to be engaged by rack teeth 121 on the lower side of rack 114, each time the upper ring is advanced. It is seen that 40 as the cam 102 rotates with shaft 63 that the links 93 and 96 are oscillated, thereby causing the bell crank 91, the link 112 and the rack 114 to oscillate. This rack 114 drops downwardly and engages the notches 120 in the upper rings 26 and 45 27, and advances them a predetermined amount depending upon the throw of the cam 102, and the adjustment made in sleeve 94 by means of set screw 98.

It is evident that if the throw of the cam is 50 small that the rack 114 will advance the ring forward a small amount, whereas, if the throw is great the upper ring will be advanced a greater amount. When the ring has been advanced the rack 114 immediately rises and moves backwardly 55 to its normal position, thus preventing the scraping effect of the rack teeth in the bottom of the rack upon notches 120 in the rings 26 and 27.

The means for raising the rack 114 upwardly after the ring has been advanced is accomplished 60 by means which will be presently described. Rack 114 has a groove 122 therein, in which is adapted to slide a plate 123, said plate 123 being held by lug 124, which is fixedly secured to rod 125. The lower end of rod 125 is slidably mounted in a lug 126, which lug is secured to the lower side of bar 97. The upper end of rod 125 slidably penetrates supporting member 99 and has disposed around the rod beneath the supporting member 99 a compression spring 127, the lower 70 end of said compression spring being confined around rod 125 by means of a fixed collar 130.

The upper end of rod 125 as seen in Figure 5 has secured thereto a cam lever 132 which contacts cam 133, said cam 133 being fixedly mount- 75

ed on shaft 63. It is seen that spring 127 tends to normally force the rod 125 and cam lever 132 downwardly against the cam at all times, whereas, the cam 133 restricts the downward movement of this rod. Cam 133 is so positioned on shaft 63 that immediately after the rack 114 has advanced the ring comprising members 26 and 27 to its farthermost position that the high portion of cam 133 will contact cam lever 132, thus causing the rod 125 and the rack 114 secured thereto to immediately rise. At this time the cam plate 102 will be in a position so that it will allow the bell crank 91 to release the pressure through link 112 on rack 114, and allow it to return to normal position under the tension of spring 117.

When the upper ring is ready to be advanced again for the cutting of another tuft of yarn, the low side of the cam 133 is contacted by cam lever 132, which again allows the rack 114 to be lowered and engage the notches 120. In this manner there is no grating effect of the teeth 121 upon the notches 120 in the upper ring, when the rack is allowed to return to normal position, thus causing the machine to operate with less noise. After the rack 114 advances the upper ring the predetermined amount, the knife 31 and its associated parts are caused to move downwardly as shown in Figure 3 to sever the yarn. This is accomplished by the cams and levers which have been previously described.

Secured to the left-hand portion of support 87 as shown in Figure 3 is a bar 141, which projects upwardly and has secured intermediate its ends as at 142 another supporting bar 99. To the upper end of rod 141 is secured a collar 143, which encircles the shaft 63 and supports the mechanism associated with rings 20, 26 and 27.

Secured to the right-hand portion of support 40 87 (Figures 2, 3 and 7) by any suitable means such as screw 145 is a strand guiding means 144. It will be noted that three rows of holes in the upper portion of guiding member 144 are provided which will enable the yarn to be guided 45 into the ring in any desired position. The top row of holes is denoted by the reference character 147, the center row by the reference character 148 and the lower row by the reference character 149.

50 It is evident that if one wishes the yarn to assume the upper position in the slot 150 in the rings 26 and 27, that the yarn will be guided to one of the holes in the upper row 147, while if a central position is desired it will be fed through 55 the center row and likewise for the yarn to occupy the lowermost position in the ring the yarn is fed through the lowermost row 149.

In Figures 2, 4 and 7 only four strands of yarn are shown being fed to the ring, but it is evident 60 that fewer or a greater number of strands of yarn can be fed to the apparatus as may be desired. The upper half-rings 26 and 27 have slot 150 extending therearound in which the strands of yarn are held.

65 At this point it should be noted that it is sometimes desirable that the yarn be treated in a suitable moistening solution before it is fed into the slot 150, in order that it will assume a more compressed and compact position, which will 70 make the yarn more favorable for cutting as well as for handling in the subsequent operations which will be later described. In order to accomplish this I provide a suitable extension table 152, upon which is mounted suitable supporting members 153 and 154.

In the upper ends of these supporting members is mounted a suitable rod 155 upon which is mounted a plurality of spools of yarn 156. It is obvious also that this can be constructed to accommodate a greater or a fewer number of spools 5 of yarn.

Secured to supports 153 and 154 by any suitable means such as screws 158 and 159 is a horizontally disposed guide bar 157. As the strands pass off the spools 156 they are guided through 10 suitable holes in bar 157, and then downwardly beneath a bar 160, disposed in container 161 which container is adapted to contain a suitable treating solution 163 such as water, oil, gasoline, emulsions, dyestuffs, or mixtures thereof. 15

Container 161 is supported on table 152 and has mounted on the upper end thereof a pair of rolls 164 and 165, between which the strands of yarn pass after leaving the bar 160. Bar 160 has a suitable handle 160a which is used for removing support 160 from the container 161. After the yarn leaves the rolls 164 and 165 it passes upwardly and through a suitable hold in a bracket 166, which is in turn secured to horizontally disposed bar 157. 25

By passing the yarn between the rolls 164 and 165 the excess treating solution is extracted from the yarn but allows a certain amount of the solution to remain in the yarn which will cause the yarn to compress and work more easily. When the yarn leaves the bracket 166 it goes to the guiding member 144, and from this point to the slot or groove 150 in the upper dial ring comprising members 26 and 27. 30

Secured to support 87, as at 171, is a plate 172 and another plate 173, said plate 172 being disposed beneath the wheel 174, and plate 173 being disposed above the wheel 174, which will cause a slot to be formed therebetween, in which the strand or strands of yarn are adapted to be guided 40 into the main slot 150. Wheel 174 is rotatably mounted as at 175 on bar 176, said bar 176 being pivotally secured to bar 87, as at 177. The other end of bar 176 has a slot 178 therein in which is adapted to be received a suitable screw 179, said 45 screw 179 penetrating this slot and being threadably secured in cross bar 19. Whenever it is desired to move the wheel 174 inwardly or outwardly in the slot 150 to accommodate a greater or lesser number of strands of yarn, the arm 176 is 50 moved inwardly or outwardly by manipulating set screw 179.

By referring to Figures 4 and 12, it is seen that a suitable plate 180 is mounted on the lower ring 20. The lower portion of member 180 has a slot 182 therein, which is penetrated by a set screw 181. The upper portion of member 180 has a lip 183, which enters the groove 150 and confines the yarn therein. By means of slot 182 it is evident that minute adjustment of the position 60 of lip 183 in slot 150 can be obtained. A similar member 184 is secured to the lower portion of ring 20, but any suitable means such as set screw 185. This member is identical in cross-section 65 in all respects to the member 180 and serves the same purpose, and a showing of this member in detail is not deemed necessary since set screw 185 penetrates a slot similar to slot 182 in member 180.

The yarn passes through the guide 144 and 70 then between plates 172 and 173 into the slot 150 in the upper ring. Then the wheel 174 compresses the yarn more firmly into the slot and from this point the member 184 prevents the escaping of the yarn from the slot 150. 75

While the yarn is being severed a tension applying means is applied to the strand. This means is provided by securing a bracket 188 to the support member 34, and this member 188 has an outstanding leg to which is pivotally secured as at 189 a plate 190. The left-hand edge of plate 190 as shown in Figure 4 has an arm 191 which is engaged by a spring 192, said spring 192 extending upwardly as shown in Figure 8, and being penetrated by a suitable set screw 193, which set screw is threadably secured in supporting member 34.

The upper end of the spring 192 normally rests against the supporting member 34, which causes tension to be applied at all times against arm 191. It is evident then that the other edge of plate 190 will be forced into slot 150 of the upper ring. A suitable plate 194 has its lower edge resting upon arm 191, which normally holds the arm in position, and this plate is pivoted as at 195 to supporting member 34.

After the yarn has been severed in the desired lengths, it is transferred by movement of the ring, step by step, to the position where it will be transferred from the slot to beneath the presser foot of the sewing machine.

By referring to Figure 16 it can be seen that another hub 196 is secured on shaft 14 and disposed on the opposite side of plate 15 from the position of hub 72, in Figure 2. Slidably mounted in the face of this hub is a plate 197 which has secured on one end thereof a rod 198, said rod 198 having integral therewith projecting portions 199 and 200. These portions 199 and 200 have notches 201 and 202 respectively cut therein, which are adapted to receive a tuft of yarn. The leaf-springs 203 and 204 are secured to rod 198 and are disposed opposite the notches 201 and 202 and serve to yieldingly hold the severed tuft of yarn in the notches 201 and 202, as it is being transferred from the groove 150 in the ring to the presser foot where it will be sewed onto a suitable fabric.

Plate 197 has a suitable slot 206 therein, into which a projection 207 is adapted to fit. Projection 207 is integral with lever arm 208, which projects upwardly and is secured to a stud 209, said stud 209 penetrating plate 15 and has secured on the other end thereof (Figure 2), a suitable lever arm 210. Arm 208 projects upwardly beyond the pivot point 209 and has a button 211 on the far side thereof, which is adapted to slidably contact the plate 15. This merely helps to make the plate more rigid and to resist lateral thrusts which are imparted to the shaft 209. Pivotedly secured in the upper end of arm 210 (Figure 2), as at 212 is the lower end of lever arm 213, said lever arm 213 being pivotally mounted as at 214 to plate 15.

By referring to Figure 14 the upper end of lever 213 and its relation to the cam is shown more clearly. The upper end of lever 213 contacts cam 215 at all times, said cam 215 being fixedly secured to shaft 63. A tension spring 216 has one end secured to the upper end of lever 213, and its other end secured to a suitable spring perch 217, said spring perch 217 being secured to the plate 15. This spring causes the upper portion of lever 213 to contact cam 215 at all times.

It is seen that when shaft 63 and cam 215 rotate clock-wise in Figure 14, that the upper portion of lever 213 will move to the right thus causing the lower portion of lever 213 as shown in Figure 2, to move to the left. This movement

will, in turn, cause the upper portion of the lever 210 to rotate to the left in a counter-clockwise manner. This movement of lever 210, as shown in Figure 2, will cause a clockwise movement of lever 208, as shown in Figure 16, 5 which, in turn will cause the projection 207, which fits into slot 206 of plate 197, to move member 197 and its associated parts upwardly to a position where it will engage the severed tuft of yarn. 10

In Figure 16 the position of plate 197 is shown just prior to the final upward movement of the plate 197 where it will engage the strand of yarn. In Figure 18 the hub 196 has made a slight rotation to the left, and the plate 197 has moved 15 upwardly due to the action of the cam just described.

It should be noted that the springs 203 and 204 are broader than the radial slots 30 in the upper ring and do not enter them but engage the 20 lower lip portion of the ring, whereas, the members 199 and 200 are narrow enough to penetrate their respective slots 30 in the ring member. This causes the tuft clamping means to spread and the spring members 203 and 204 are 25 removed from the arms 199 and 200 and members 199 and 200 are then moved upwardly behind the tuft and will allow the tuft to enter the notches 201 and 202.

When the tuft clamping means has moved upwardly and has rotated to the position shown in Figure 18, and has moved the tuft out of the groove, the springs 203 and 204 move to their normal position and yieldingly clamp a tuft of yarn in its proper position. After the tuft of 30 yarn has been grasped, as shown in Figure 18, the plate 197, together with the hub 196 is rotated to the position shown in Figure 19 by means of the cams 77 and 80 and their respective levers 15 and 79. At this point the upper portion of the lever 213 again contacts a high portion on cam 215 and causes the lever 208 to oscillate slightly in a counter-clockwise direction, thereby forcing the plate 197 and its associated parts to a position shown in Figure 24, 40 where the tuft of yarn is placed beneath the presser foot 220, and maintained in proper formation by the tuft clamping means straddling the needle and presser foot and moving in timed relation with the feed until the tuft is stitched to the base fabric. At this position the tuft clamping means quickly rises and then oscillates again in the opposite direction, and assumes a 45 position as shown in Figure 16 ready to clamp the next tuft. 50

It is seen in Figure 19 that when the plate 197 is in this position that a slight clearance exists between the lower side of projection 207 and the slot 206, which is cut in plate 197. This construction is used in order to allow a slight clearance so that when the tuft clamping means is moved downwardly and is pressed against a previously stitched tuft or an excessively thick piece of goods that the plate 197 will be allowed to move slightly upward, thus preventing any damage to the tuft clamping means or materials. 55

The mechanism is synchronized throughout so that when the upper ring is moved to the proper position, the knife operates in timed relation to the yarn clamping means. After the knife has 60 severed the yarn, the knife immediately withdraws from the slot, and the ring is advanced a predetermined amount. In the meantime the tuft clamping means rises and clamps a tuft of 65 yarn while another tuft of yarn is being cut by 70 75

- the knife. While the tuft clamping means is transferring the yarn beneath the presser foot the ring is given a partial rotation and a similar operation is repeated.
- 5 By using the present tuft clamping device with two prongs thereon, it is obvious that the tuft of yarn will have to be an odd number of notches in length in order to make the yarn symmetrical about the sewing line. For example, in the present instance, a tuft must be not less than three notches wide. This means that the upper ring will have to be advanced at least three notches for each operation of the cutting knife.
- 10 Secured to the presser foot 220, as at 226, is a member 225, which extends outwardly beside the presser foot 220, and has secured on the end thereof U-shaped member 227. Needle thread 228 passes through a conventional needle 229 and then downwardly through the fork of the presser foot 220, and then upwardly through the U-shaped member 227 where it is severed by a cutting edge 230. The end of the thread is held in this position shown in Figure 21, when the fabric is removed from beneath the presser foot, 15 and it is desired that the needle thread be clamped and held in position while the machine is in inoperative position.
- 15 Means have also been shown in the lower portion of Figure 16 and in Figure 17 for cutting and holding the bobbin thread after the fabric has been removed from the machine. This is comprised of a member 231, which is pivotally secured to the lower side of throat plate 232 by any suitable means such as a screw 233, which 20 penetrates hole 234 in member 231. Member 231 has an arm 235 which is adapted to fit into groove 236 in throat plate 232. In normal position this arm 235 is held beneath the top surface of the throat plate. This arm 235 has a 25 hook portion 236 beneath which the thread is clamped when in inoperative position, said plate having a cutting edge 237 for cutting the thread. Member 231 also has another downwardly projecting member 238, and the end of this member has a spring 239 engaging the end thereof, and the other end of spring 239 rests against the 30 lower portion of throat plate 232, which normally holds the arm 235 beneath the top surface of the throat plate.

for holding the belt in the proper position on the cone pulleys 271 and 273.

Pivoted secured as at 300 is a vertically disposed lever 301 which is pivoted intermediate its ends as at 302 to a notched rack 303. Disposed below point 302 is a suitable lever 304 for the manipulation of the belt guide.

Figures 26 to 31 inclusive, show a modified form of the invention in which means for feeding a tuft of yarn of very short length can be effected. In the previous mechanism described, a tuft of yarn must be three, five or seven notches in length or any odd number of notches in length in order to be symmetrical about the stitched line when sewn to the fabric. By using the mechanism in this modified form it is possible to deliver a tuft of yarn of an even number of notches in length to sew it symmetrically about its center line. In this modified form I provide a pin 310 (Figure 30) which is fixedly secured in plate 197.

Pin 310 has integral therewith a rigid member 311 which has in the lower end thereof a notch 312, in which the severed portion of yarn is adapted to fit. A spring 313 is also integral with pin 310 and acts in the same manner as either spring 203 or 204 acts in conjunction with rigid members 199 and 200 (Figure 23).

It has been found that it is impossible to place the tuft of yarn any nearer the presser foot than is shown in Figure 26, with the tuft clamping means, and there are several changes in this form of the invention that must be made to stop the rotative movement of hub 72 and plate 197 when it falls to the position as shown in Figure 26, so that spring 313 will not engage the toe of the presser foot 220. A cam 315 (Figure 28) is fixedly secured on shaft 63, and is very similar to the cam 215 shown in Figure 14, but is so shaped that the movement of plate 197 and its associated parts 311 and 313 will move downwardly to deliver the tuft of yarn to the fabric immediately after it assumes the position which is shown in Figure 26.

Suitable cams 316 and 317 (Figure 27) are also fixedly secured to shaft 63. These cams are similar to cams 80 and 11 respectively, as shown in Figure 2; however, they are modified to control the oscillation of the hub 72, in order that it will stop when it has rotated the hub 72, plate 197 and its associated parts 311 and 313 to the position shown in Figure 26.

After the tuft of yarn has been delivered to the fabric, other means are provided for grasping the tuft of yarn and conducting it beneath the presser foot 220. A forked member 318 having hooked members 319 and 320 are disposed to move downwardly with members 311 and 313 when the tuft of yarn is in the position shown in Figure 26, and pull the tuft of yarn to the left and conduct it beneath the presser foot 220. This downward and rearward motion of the hooks 319 and 320 is effected by the cams 321 and 322 mounted on shaft 63.

Cam 322 is secured to a hub 325 by any suitable means such as a stud bolt 324, said stud bolt piercing a slot 326 in the cam plate 322. Cam 322 and its associated parts are similar in all respects to the cam 102 as shown in Figure 6 and may be adjusted with relation to the upper portion of lever 327. Lever 327 is integral with member 318 and is pivoted as at 328 to plate 15. A slot 329 is provided to allow a slight vertical movement in the lever 327.

It is seen by referring to Figure 26 that the cam 322 oscillates the lever 327 and causes the

hook members 319 and 320 to move back and forth for each revolution of shaft 63. It is further seen that a suitable cam arm 330 is adjustably secured to the upper end of lever 327 and this arm 330 is adapted to contact the upper portion of cam 321.

The lever 327 is normally pressed against the cam 322 by any suitable means such as a tension spring 331, which has one end secured to the lower portion of lever 327 and its other end secured as at 322 to plate 15. In the position of the cams shown in Figure 26, it is evident that as the cam 321 rotates in a clockwise direction the lever 327 and its associated parts will be lowered thus allowing the hook members 319 and 320 to engage the tuft of yarn. When this is lowered, it is seen that the high side of cam 322 will engage the lever 327 and cause the lower portion of lever 327 and its associated parts to conduct the tuft of yarn beneath the presser foot 220 where it will be sewed to the fabric. As has been stated, this attachment provides means whereby a tuft of yarn of an even number of notches in length can be sewed to the fabric.

The other portions of the mechanism are similar in all respects and it is not deemed necessary that a description of these parts be repeated. It is evident from the drawings, however, that the hook members 319 and 320 move forwardly toward the front of the machine in an elevated position as shown in Figure 26, and then upon further rotation of the shaft, the hook members are allowed to drop down upon the fabric and then move rearwardly under the cam 321 until the tuft of yarn is conducted beneath the presser foot 220. It again rises in elevated position over the tuft of yarn and repeats this operation.

Figure 24 shows a sectional view in which the fabric 335 is fed beneath the presser foot 220, and tufts of yarn 336 are being sewed thereto, by means of the first mechanism described. In Figure 33, six strands of yarn, namely 337, 338, 339, 340, 341 and 342 are shown disposed within groove 150 of the upper ring. This is shown for purely illustrative purposes, while it is apparent that any number of strands may be used.

The strands as shown in Figure 33, when conducted to the fabric will be disposed in an upside down position from that shown in Figure 33, since the tuft of yarn after it has been severed will be turned approximately 180 degrees, when it is delivered upon the fabric.

In order to show how a varied colored effect can be produced, let us assume that a strand of yarn 341 is made of some particular color whereas the other strands are all of the same color. Figure 34 shows the position of the strand 341 after it has been sewed to the fabric 335.

Figure 35 shows the position of this same strand 341 after it has been fluffed. It is apparent that this will bring out a varied color scheme, for example, with a colored dot in the center and the remainder of the fluff portion being uncolored. Figure 36 shows still another effect that can be produced when the strand 338 is of a colored material, and the remaining strands of another color.

In Figure 37 the position of strands 337 and 340 and strands 339 and 342 are shown when the tuft of yarn has been fluffed. It is evident that these strands could be of a colored material, whereas, the remaining strands could be uncolored and produce still another color effect.

Figure 38 shows the position of strands 337 and 339 when the tuft of yarn has been fluffed. Like-

wise, should these strands be of colored material, four colored dots would appear in the periphery of the fluffed portion.

These examples are merely shown to illustrate 5 the various color schemes that can be produced by the use of my apparatus. It is evident however that any number of color schemes could be shown and it is not deemed necessary to show any more than is necessary to disclose the purpose of the invention.

It is frequently desirable at the beginning or end of a course of stitches to reverse the oscillation of the feed plate and the direction of travel of the cloth, and to sew the tuft more securely at the beginning or end of the line of stitches and to prevent the stitches from unravelling. In Figure 32 I have provided means for reversing the direction of oscillation of the conventional feed plate.

20 By reversing the oscillation it is obvious that the direction of travel of the cloth will be reversed and consequently the end stitches will be reinforced because more stitches will be placed at the point where it is reversed. The conventional feed plate 342 is operated by the feed plate shaft 343, upon which is fixedly mounted a lever 344.

30 Pivotedly secured at the end of this lever, as at 345, is a vertically disposed link 346, which contacts at the upper end thereof an eccentric cam 347 mounted on shaft 280. Pivotedly secured to the upper portion of link 346, as at 348, is another link 349 which projects downwardly and has pivotally secured at its lower end bell 35 crank 351. This bell crank is pivoted to the standard 11, as at 352, and projects to the left, as shown in Figure 32, penetrating a slot 353 in the standard 11.

On the left-hand end of the bell crank 351 is 40 threadably secured a handle 354. An angle member 355 having a slot 356 in the vertical leg is secured between handle 354 and bell crank 351. The outstanding leg 357 of angle member 355 projects into slot 353. It is evident that by loosening 45 the handle 354 and adjusting the height of angle member 355 that the downward movement of bell crank 351 can be varied.

A suitable tension spring 358 is secured to 50 handle 354 and has its lower end secured to the housing of standard 11, as at 359.

When bell crank 351 is so positioned that the center of shaft 280, point 350 and point 345 are in direct alinement, the rotation of cam 347 will not produce any vertical movement or any oscillation in feed plate shaft 343. However, when the bell crank 351 is so positioned that point 350 will fall to the right of a line drawn through the center of shaft 280 and point 345, the shaft 343 and the feed plate will oscillate in a conventional manner. By raising the bell crank 351 so that the point 350 will fall to the left of the line drawn through the center of shaft 280 and 55 345, the oscillation of feed plate shaft 343 will be reversed, thus the travel of the cloth beneath the presser foot will be reversed. The spring 358 is provided so that when the direction of oscillation of the feed plate 342 is desired to be reversed from the conventional manner that the handle 354 can be moved upwardly in slot 353 and held 60 65 in this position manually until the direction of travel is desired to be returned to the conventional manner.

In the drawings and specification there has been set forth a preferred embodiment of the 70 invention, and although specific terms are em-

ployed they are used in a generic and descriptive sense only, and not for purposes of limitation, the scope of the invention being set forth in the appended claims.

I claim:

1. In a sewing machine having a reciprocating needle carrying a sewing thread and having means for feeding a fabric through the machine, a yarn conveyor, a reciprocating knife, means for feeding a strand of yarn into said conveyor, 10 means for advancing the yarn conveyor step by step in the path of said reciprocating knife to cause said strand of yarn to be intermittently severed, and means for seizing the severed portions and intermittently delivering the same in 15 advance of the needle, to be sewed onto the fabric.

2. In a sewing machine having a reciprocating needle carrying a sewing thread and having means for feeding a fabric through the machine, 20 a reciprocating knife, a yarn conveyor carrying a strand of yarn comprising a rotatable ring member, means for advancing said conveyor, step by step, in timed relation and in the path of said reciprocating knife to cause said strand of yarn to 25 be intermittently severed, and means for seizing the severed portions and intermittently delivering the same in advance of the needle to be sewed onto the fabric.

3. Means for sewing severed strands of yarn to 30 a fabric comprising a sewing machine having a presser foot and a reciprocating needle carrying a sewing thread, means for delivering a strand of yarn to the sewing machine, means for intermittently severing the strand of yarn into short 35 lengths, means for transferring the severed lengths of yarn onto the fabric slightly in advance of the presser foot, and means for engaging said lengths to guide the same beneath the presser foot.

4. In a sewing machine, means for feeding a 40 fabric through the machine, means for feeding strands of yarn thereto, means for severing the strands into a plurality of portions, and means for seizing the severed portions and delivering the same in advance of the needle to be sewed onto the fabric.

5. A sewing machine having a reciprocating needle for piercing a fabric and means for delivering a sewing thread to the needle, means for supplying a strand of yarn to the sewing machine, means for cutting the strand into short lengths of yarn, means for transferring the lengths to the fabric and the needle to be sewed onto the fabric, and means for adjusting the feed of the yarn to vary the lengths cut therefrom, and means for varying the operation of the transferring means with relation to the travel of the fabric to space the position of the lengths on the fabric.

6. A sewing machine having a reciprocating needle and means for supplying a sewing thread to the needle, means for feeding a fabric past the needle, rotatable means above the fabric and having a peripheral groove therein, means for feeding a plurality of different colored strands of yarn to said groove, means for compressing the strands to form one strand of different colors, a cutter for cutting the strands into given lengths, means for transferring the lengths of yarn from said groove to the fabric and feeding them to the means for feeding the fabric through the machine and holding the lengths until the line of stitches formed by the needle sews the lengths to the fabric.

7. A tufting machine comprising a reciprocating needle and means for feeding a thread to the needle, means for feeding a fabric past the needle, means for feeding a tufting strand to a point removed from the needle, means for severing the strand, means for seizing the severed portions of the strand, and feeding the same to the needle to be sewed to the fabric and means for timing the rate of feed of the severed portions to thereby regulate the position of the tufts on the fabric. 5
8. A sewing machine having a reciprocating needle provided with means for feeding a sewing thread to the needle to form a line of stitches on a fabric, means for feeding a fabric past the needle, a rotary member disposed above the needle and having a peripheral groove therein and also having a plurality of radially disposed grooves crossing said peripheral groove, means for feeding a strand to said peripheral groove, 10 means for intermittently moving the rotary member, a reciprocating cutter, means for intermittently moving said cutter into certain of said radial grooves to sever the strand, means for seizing the severed portions of the strand and transferring said portions to said fabric in front of the needle. 15
9. A sewing machine having means for feeding a fabric therethrough and having yarn feeding means, means for cutting the yarn into tufts, 20 and means for feeding the tufts to the surface of the fabric to be sewed thereto by the sewing machine. 25
10. A tuft forming machine comprising a reciprocating needle provided with a sewing thread, means for feeding a fabric past the needle, means for holding bunches of yarn of the desired length and in sufficient quantities to make a tuft and means for intermittently feeding the bunches of 30 yarn from the holding means to the fabric in advance of the needle to be sewed onto the fabric. 35
11. A tuft forming machine comprising a reciprocating needle provided with a sewing thread and having means for feeding a fabric past the needle, means for cutting a strand of yarn into tufts and means for feeding the tufts, one at a time, to the fabric and the needle to be sewed onto the fabric, and means for reversing the direction 40 of travel of the fabric. 45
12. A tuft forming machine comprising a reciprocating needle provided with a sewing thread and having means for feeding a fabric past the needle, means for cutting a strand of yarn into tufts, means for feeding the tufts, one at a time, to the fabric to be sewed thereto by the needle, and means for adjusting the operation of the cutting means to vary the length of the tufts. 50
13. A tuft forming machine comprising a reciprocating needle provided with a sewing thread and having means for feeding a fabric past the needle, means for cutting a strand of yarn into tufts, means for feeding the tufts, one at a time, to the fabric to be sewed thereto by the needle, and means for adjusting the feeding means with 55 relation to the travel of the fabric to thereby regulate the spacing of the tufts on the fabric. 60
14. A sewing machine having a reciprocating needle, means for feeding a fabric to the needle, a magazine for holding bunches of short strands cut to the desired length and means for intermittently feeding bunches of said relatively short strands to the needle to be sewed onto the fabric in spaced relation to form tufts. 65
15. A sewing machine having a reciprocating needle and means for passing a fabric through the machine, means for supplying a sewing thread to the needle, means for delivering tufts of material to the needle to be sewed to the fabric and means for timing the rate of delivery of the tufts to regulate the spacing between the tufts on the fabric. 70
16. In a machine for sewing tufts on fabric having a reciprocating needle and means for feeding a sewing thread to the needle, a rotary member disposed above the needle and having a peripheral groove therein, means for feeding a strand to said groove as the member rotates, means for severing the strand into relatively short lengths, means for seizing said severed portions and transferring them to the fabric in front of the needle whereby the line of stitches formed by the needle will traverse the severed portions and sew them to the fabric. 75
17. Means for sewing severed strands of yarn to a fabric, comprising a sewing machine having a reciprocating needle carrying a sewing thread, means for delivering a strand of yarn to the sewing machine, means for intermittently severing the strand of yarn into short lengths, means for transferring the severed lengths of yarn onto the fabric and delivering the same to the needle to be sewed onto the fabric. 80
18. Means for sewing severed strands of yarn to a fabric, comprising a sewing machine having a reciprocating needle carrying a sewing thread, means for delivering a strand of yarn to the sewing machine, means for intermittently severing the strand of yarn into short lengths, means for transferring the severed lengths of yarn onto the fabric and delivering the same to the needle to be sewed onto the fabric, and means for varying the rate of travel of said severing and transferring means. 85
19. In a sewing machine having a reciprocating needle with a sewing thread therein, a reciprocating knife, a yarn conveyor, means for feeding yarn to said conveyor, said conveyor comprising a toothed rotatable ring member, a rack member for engaging said teeth to advance said yarn conveyor step by step in the path of said reciprocating knife, means for raising said rack out of engagement with said teeth after the conveyor has been advanced to allow the rack to return to normal position, and means for severing the strands into a plurality of portions and intermittently delivering the same in advance of the needle to be sewed onto the fabric. 90
20. Means for sewing severed strands of yarn to a fabric, comprising a sewing machine having a reciprocating needle carrying a sewing thread, means for delivering a strand of yarn to the sewing machine, means for intermittently severing the strand of yarn, and means for transferring the severed lengths of yarn onto the fabric and delivering the same to the needle to be sewed onto the fabric. 95
21. A sewing machine having a reciprocating needle for piercing a workpiece, means for forming tufts on said workpiece comprising apparatus for holding severed lengths of yarn, and means for engaging the severed lengths and feeding the same to the surface of the workpiece in front of the advancing needle to be sewed onto the workpiece by the advancing needle. 100
22. A sewing machine having a reciprocating needle for piercing a workpiece, means for forming tufts on said workpiece which comprises an apparatus for holding a supply of relatively short 105

- lengths of severed yarn, means for engaging a bunch of said severed lengths of yarn and feeding the bunch to the needle and holding the same until the turf is formed on the workpiece from 5 said bunch of yarn.
23. Apparatus for forming turfs on a workpiece comprising a sewing machine having a reciprocating needle for penetrating said workpiece, means for holding a supply of short lengths 10 of yarn, means for engaging a quantity of said lengths of yarn and conveying the said quantity to the needle and holding the same until said quantity is sewed to the workpiece.
24. A sewing machine having a reciprocating needle for piercing a workpiece, means for holding a supply of yarn cut into short lengths, means for engaging a bunch of said short lengths and conveying the same to the needle and holding the same while the bunch is sewed to the fabric. 15
25. A sewing machine having a reciprocating needle for piercing a workpiece, means for sewing turfs to the workpiece comprising means for holding a supply of relatively short lengths of yarn cut to desired length, and means for intermittently engaging a portion of said cut yarn and conveying the same to the needle and holding the same while the cut yarn is sewed to the workpiece. 20
26. Apparatus for making tufted rugs and the like from a suitable workpiece which comprises a sewing machine provided with a reciprocating needle for penetrating the workpiece, and means for holding a supply of cut yarn, means for intermittently engaging bunches of said yarn and conveying them to the workpiece in advance of the needle and holding the bunches while they are sewed to the workpiece by the reciprocating needle. 25
27. In a sewing machine having a reciprocating needle carrying a sewing thread and having means for feeding a fabric through the machine, means for holding yarn cut into predetermined lengths, and means for seizing a bunch of cut yarn and feeding the same to the needle to be sewed to the fabric. 30
28. In a sewing machine having a reciprocating needle carrying a sewing thread and having means for feeding a fabric through the machine, means for holding a supply of yarn cut to predetermined lengths, and means for intermittently seizing a bunch of the cut yarn and feeding the same to the fabric in advance of the needle and holding the yarn until it is sewed to the fabric by the needle. 35
29. A sewing machine having a reciprocating needle provided with a sewing thread, means for holding a supply of yarn cut to desired lengths, and means for intermittently engaging a bunch of cut yarn from said supply and transferring it to the needle and holding the bunch while it is sewed to the fabric by the needle. 40
30. A sewing machine having means for feeding a fabric therethrough, means for holding a supply of yarn cut into tufts, and means for feeding the tufts to the surface of the fabric to be sewed thereto by the sewing machine. 45
31. A sewing machine having means for feeding a fabric therethrough, means for holding a supply of yarn cut into tufts, and means for intermittently engaging a tuft of yarn and mov- 50
- ing it to the surface of the fabric to be sewed thereto by the sewing machine.
32. In a sewing machine having a reciprocating needle provided with a thread, means for feeding a workpiece relative to the needle, means for intermittently feeding tufts of yarn to the workpiece in front of the needle, and means for varying the rate of feed of the tufts relative to the rate of feed of the workpiece to thereby space the tufts the desired distance on the workpiece. 55
33. In a sewing machine having a reciprocating needle carrying a sewing thread and having means for feeding a fabric through the machine, means for holding a supply of yarn cut to predetermined lengths, and means for intermittently seizing a bunch of the cut yarn and feeding the same to the fabric in advance of the needle and holding the yarn until it is sewed to the fabric by the needle, and means for changing the rate of feed of the tufts relative to the rate of feed of the fabric to thereby secure the desired spacing of the tufts on the fabric. 60
34. A sewing machine having means for feeding a fabric therethrough, means for holding a supply of yarn cut into tufts, means for feeding the tufts to the surface of the fabric to be sewed thereto by the sewing machine, and means for changing the rate of feed of the tufts relative to the rate of feed of the fabric to thereby secure the desired spacing of the tufts on the fabric. 65
35. A sewing machine having means for feeding a fabric therethrough, means for holding a supply of yarn cut into tufts, means for intermittently engaging a tuft of yarn and moving it to the surface of the fabric to be sewed thereto by the sewing machine, and means for changing the rate of feed of the tufts relative to the rate of feed of the fabric to thereby secure the desired spacing of the tufts on the fabric. 70
36. A tuft forming machine comprising a reciprocating needle provided with a sewing thread and having means for feeding a fabric past the needle, means for cutting a strand of yarn into tufts, means for feeding the tufts to the fabric to be sewed thereto by the needle, and means for adjusting the operation of the cutting means to vary the length of the tufts. 75
37. A tuft forming machine comprising a reciprocating needle provided with a sewing thread and having means for feeding a fabric past the needle, means for cutting a strand of yarn into tufts, means for feeding the tufts to the fabric to be sewed thereto by the needle, and means for adjusting the tuft feeding means with relation to the travel of the fabric to thereby regulate the spacing of the tufts on the fabric. 80
38. A sewing machine provided with means for holding cut lengths of yarn and means for feeding the cut lengths of yarn onto the surface of a fabric in spaced relation to each other to be sewed to the fabric by the needle of the sewing machine. 85
39. In a sewing machine provided with a needle and fabric feeding means, means for holding cut lengths of yarn and means for feeding the lengths of yarn to the surface of the fabric in advance of the needle to be sewed to the fabric by the needle. 90
